COMBINATION CAP AND LID FOR CONDIMENT DISPENSERS WITH SEALING MEANS FOR CAP APERTURES

Frank P. Daniell, Benavides, Tex.

Application June 28, 1948, Serial No. 35,695

8 Claims. (Cl. 222—517)

1

This invention relates to condiment dispensers such as containers for salt, pepper, spices and other condiments, and more particularly to a cover for a container. This application is a continuation-in-part of my copending application Serial No. 757,855, filed June 28, 1947 which has been abandoned.

It is characteristic of table salt that it has an affinity for moisture and when damp it will not flow freely. The apertures in the caps for the customary type of salt shaker become clogged with caked salt when the salt is damp. It is one of the objects of the present invention to provide a cover adapted to seal the apertures of a salt shaker cap against the entrance of moisture.

It is a further object of the invention so to form the cover and apertures that each aperture is individually sealed.

It is also an object of the invention to provide a supplemental seal completely surrounding the apertures further to prevent the entrance of moist air and to protect the cover against contamination thereby to form a completely sanitary closure.

Other objects will be apparent from the following description of a preferred embodiment of the invention taken in connection with the accompanying drawings, in which:

Fig. 1 is a perspective view of the cap and lid attached to a container;

Fig. 2 is a vertical section taken through the cover and container;

Fig. 3 is a section taken on line 3—3 of Fig. 2; and

Fig. 4 is a bottom plan view of the lid, parts thereof being broken or in section.

In the drawings, the container, which may be formed from glass or other suitable material, is indicated at 10 and is provided with a threaded neck portion 11 adjacent the open end thereof. Adapted to be threaded on the neck is a cap 12 from the upper surface of which project a plurality of regularly arranged cone shaped protuberances 13 and a raised circumferential sealing rim 14, the cones all lying within the peripheral rim. Each of the cones is apertured at 15, as shown, the openings being tapered toward their upper or discharge ends. It is to be noted that the taper of the cones is greater than that of the apertures and that they converge at the upper or apical ends of the cones to provide a circular sharp edge around each aperture. The peripheral rim is likewise tapered and has converging surfaces which form a similar sharp edge. It will also be observed that the upper ends of the

2

cones and the edge of the rim all lie in a single plane.

Pivottally attached to ears 16 on the cap is a lid 17 having a circular rib 18, shoulder 19, and button 20 on the under face thereof. These portions also lie in the same plane and overlie the cones and rim of the cap and register with them when the lid is in closed position. A spring 21 on the pivot pin 22 cooperates with lugs 23, 23' on the cap and lid respectively to urge the lid into closing position with respect to the cap. The lid is provided with an extension 24 forming a finger or thumb piece to permit the lid to be raised to open position. Gasket 25 fits tightly in the lid 17 and is made from a resilient material such as soft rubber or the like. If desired, a gasket 25' may be interposed between the cap and the container, depending upon the type of material from which the cap is made.

20 When the lid is urged to closed position by spring 21, the gasket is interposed between the shoulder, button, and ribs of the lid on the one hand, and the apertured protuberances, as well as the peripheral rim of the cap on the other hand. The ribs register with the protuberances and the rim better to form an effective seal between the gasket 25 and the sharp edges at the tops of the apertured cones and rim 14. The soft material of the gasket tends to enter the apertures and, since the latter are tapered, any grains which have become lodged at the upper ends of the apertures will be released. The material of the gasket also removes grains adhering to the outer surfaces of the cones at the sharp edges referred to.

30 It will be appreciated from the foregoing description that each cone is individually sealed and that, in addition, a seal is formed peripherally of the cap by the rim having a similar sharp edge. There is obtained, in effect, a double seal so that the air surrounding the cones is sealed off by the rim in cooperation with the gasket.

It is obvious that, while the invention has been described with respect to a container for table salt, it is equally effective to seal a dispenser for pepper, spices and other condiments to prevent evaporation of certain volatile oils therein which would result in a loss of strength in these condiments.

40 While a preferred form of the invention has been illustrated and described, it is to be understood that such modifications as fall within the terms of the appended claims are contemplated. The cap and lid are readily molded from plastics, and, in practice this type of material is preferred,

but it may be cast or pressed from metal without departing from the principles of the invention.

Having described my invention, what I claim as new and desire to secure by Letters Patent is:

1. A cover for a condiment dispenser comprising a cap adapted to be removably attached to the open mouth of a container, said cap having a plurality of cone shaped protuberances projecting from a face thereof, said protuberances having apertures extending therethrough, said cap also being provided with a raised peripheral rim surrounding said plurality of protuberances, the sides of said protuberances and said apertures, as well as the sides of said rim, converging to form a sharp edge at their upper ends, a lid pivotally attached to said cap and having a resilient gasket adapted to engage said protuberances and said rim to seal said cap and the apertures therein, and means for urging said lid and gasket into sealing relation with said protuberances and said rim.

2. A cover as claimed in claim 1 in which all of said sharp edges lie in a single plane.

3. A cover for a condiment dispenser comprising a cap adapted to be removably attached to the open mouth of a container, said cap having a plurality of cone shaped protuberances projecting from a face thereof, said protuberances having apertures extending therethrough, a lid pivotally attached to said cap and having projections registering with said protuberances when said lid is closed, a resilient gasket in said lid and interposed between said projections and said protuberances to seal the apertures therein, and means for urging said lid and gasket into sealing relation with said protuberances.

4. A cover for a condiment dispenser comprising a cap adapted to be removably attached to the open mouth of a container, said cap having a plurality of cone shaped protuberances projecting from a face thereof, said protuberances having apertures extending therethrough, said cap also being provided with a raised peripheral rim surrounding said plurality of protuberances, a lid pivotally attached to said cap and having projections registering with said protuberances and said rim when said lid is closed, a resilient gasket in said lid and interposed between said projections and said protuberances and rim to seal said cap and the apertures therein, and means for urging said lid and gasket into sealing relation with said protuberances and said rim.

5. A cover for a condiment dispenser comprising a cap adapted to be removably attached to the open mouth of a container, said cap having a plurality of cone shaped protuberances projecting from a face thereof, said protuberances having apertures extending therethrough, the sides of said protuberances and said apertures converging

to form a sharp edge at the apical end of each of said protuberances, a lid pivotally attached to said cap and having projections registering with said protuberances when said lid is closed, a resilient gasket in said lid and interposed between said projections and said protuberances to seal the apertures therein, and means for urging said lid and gasket into sealing relation with said protuberances.

6. A cover as claimed in claim 5 in which all of said sharp edges lie in a single plane and the faces of said projections lie in another single plane.

7. A cover for a condiment dispenser comprising a cap adapted to be removably attached to the open mouth of a container, said cap having a plurality of cone shaped protuberances projecting from a face thereof, said protuberances having apertures extending therethrough, said cap also being provided with a raised peripheral rim surrounding said plurality of protuberances, the sides of said protuberances and said apertures, as well as the sides of said rim, converging to form a sharp edge at their upper ends, a lid pivotally attached to said cap and having projections registering with said protuberances and said rim when said lid is closed, a resilient gasket in said lid and interposed between said projections and said protuberances and rim to seal said cap and the apertures therein, and means for urging said lid and gasket into sealing relation with said protuberances and said rim.

8. A cover as claimed in claim 7 in which all of said sharp edges lie in a single plane and the faces of said projections lie in another single plane.
